UPRIGHT PIANO

Henry R. Heller, Larchmont, N. Y.

Application March 5, 1936, Serial No. 67,218

6 Claims. (Cl. 84—177)

My present invention relates to improvements in the construction of the case and frame of upright pianos whereby greater simplicity of parts is obtained together with easier manufacture and assembling as well as a more effective mode of operation.

With these and other objects and advantages in view evident to those skilled in the art from the following disclosure, I have shown in the accompanying drawing a preferred illustrative embodiment of the invention, which will be hereinafter described with reference to the invention, and I will then point out the invention in the claims.

15 In the drawing:

Fig. 1 is a fore and aft sectional view, partly in elevation, of an upright piano construction within my invention;

20 Fig. 2 is a front elevation of the same, only the left-hand end of the piano, however, being shown;

Fig. 3 is a perspective fragmentary view to illustrate more clearly the interior construction of the foregoing; and

25 Fig. 4 is a perspective, fragmentary view of the foot and lower portion of the construction.

My present invention in part comprises cutting each side-part 10 of the case out of a single board or plank so that the arm 10a is integral with the main portion 10b and so that the leg 10c, preferably, is also integral with said arm. Each side-part 10 is secured as shown in Fig. 3, to an end of the so-called piano-back 12, which is the usual heavy-timbered frame to which the sound board 14 and the string-plate 16 are secured.

The foot 18 is a single wooden strip, preferably of rather thick cross-section, one on each side of the case, extending under the leg 10c on that side and under the bottom edge of the main portion 10b of the side-part (Fig. 4). It is reduced in width at its rear-end 18a so as to extend along the end of the piano-back 12 to which it is secured.

40 The bottom-board 20 of the piano case is secured to the bottom of the piano-back and extends forward for about one half the length of the foot members 18, to whose under side it is secured. The foot members and the ends of the legs 10c are also united.

45 22 designates cheek-pieces of generally rectangular shape, one for each side-part 10, secured to the inside face of its arm 10a, as best shown in Fig. 3. At the front and the top, these

check-pieces are or may be substantially flush with the arms 10a. They are notched out or recessed on their bottom edges at 22a (Fig. 3) to receive up into them the ends of the key-bed 24, which is secured thereto in said position. The key-slip 26 (Figs. 1 and 2) is supported at the front edge of the key bed 24 between the cheek-pieces 22 (Figs. 2 and 3). Of course the key-bed supports the key-board 28 (Fig. 1) in the usual manner.

10 Each cheek-piece 22 is formed with an L-shaped notch having a vertical limb 22b which receives the ends of the name-board 30 to finish the piano case at the back of the black-keys. The horizontal limb 22c of said notches receives the ends of the book-slip 32. The upper front panel 34 is bottomed in the rear end of said horizontal notches which are purposely made to extend beyond the rear edge of the book-slip, as best shown in Fig. 1. This upper panel 34 rests 15 at its upper portion against a stop 36 or the like secured to the inside face of each side part 10 (Fig. 1). Thus all of the aforesaid parts, namely the name-board, the book slip and the upper panel are supported so as to be readily removable 20 to enable free access when necessary to the interior parts of the piano.

15 The lower front panel 38 (Fig. 1) is likewise removably supported. For this purpose the inner face of each foot-member 18 is formed with a 25 vertical notch 18b (Fig. 4). The lower edge of this panel is receivable down into these notches and rests on the underlying bottom-board 20. (Compare Fig. 4 with Fig. 1.) The inner face of each side-part 10 is equipped with a stop 40 30 (Fig. 1) to contact with the back of the panel. A spring clip 42 mounted on the under-side of the key-bed releasably engages the upper edge of the panel to lock it in place.

Fig. 1 also shows one of the piano pedals 44 35 pivoted to a fixture 46 on the bottom-board 20 and extending forwardly through a slot in the lower edge of the aforesaid lower panel 38.

40 Castors 48 are mounted on the under-side of the foot-members 18 at the legs 10c and on the bottom of the piano-back 12 and serve to support the piano upon the floor.

45 The sides 10 with their one-piece arms 10a and legs 10c have the advantage that each can 50 be cut out of a single board. Moreover, this construction enables the outside (and inside) face of said sides to be readily sanded and finished. The cheek-pieces 22 reinforce the arm-portions of the sides and additionally conveniently sup- 55

port the upper panel 34, the book slip 32, the name-board 30, etc. The one-piece foot members 18 at their rear ends have strong attachment to the piano-back 12 and to the bottom-board 29 and the sides 10 of the case; and their front ends give firm support to the legs 10c. The notched inner faces of said foot-members overlying the bottom board 20 constitute an excellent means for detachably supporting the lower panel 38.

The aforesaid improvements accomplish all that is accomplished by the conventional piano case, which has arms and legs separate from the sides and a different foot construction, and a different means of support for the key-bed, the name-board, book-slip, and the upper and lower panels. The present improvements accomplish the foregoing by means which is simpler, more effective and less expensive to manufacture.

I have illustrated and described a preferred, satisfactory embodiment of my invention, but it will be understood that changes may be made therein within the spirit and scope of the invention as defined in the appended claims.

What I claim is:

1. In an upright piano construction, in combination, a piano-back; sides projecting forwardly from the piano-back, each having a forwardly projecting horizontal arm and a vertical leg depending from the free end of said arm, said leg and arm both being an integral part of the same board as the main portion of said side; and foot members projecting forwardly from the piano-back into supporting position under said legs.

2. In an upright piano construction, in combination, a piano-back; sides projecting forwardly from the piano-back, each having an arm which is an integral part of the same board as the main portion of said side; and cheek-pieces, one for each of said arms, rigidly secured to the inner face thereof, each cheek-piece being substantially flush at its front and top portions with

the corresponding portions of the arm to which it is secured.

3. The piano construction of claim 2 further characterized by there being a name-board, a book-slip and a front panel supported by said cheek-pieces, the cheek-pieces being notched vertically downward from their upper edge to receive the name-board, and being horizontally notched at their upper edge rearwardly from said vertical notches to receive the book-slip, 10 said horizontal notches having free rear-ends wherein rests the lower edge of the front panel.

4. The piano construction of claim 2 further characterized by there being a key-bed supported by said cheek-pieces, the lower edge of the side-cheeks being recessed and the key-bed being received up into said recesses and secured to the cheeks.

5. In an upright piano construction, the combination of a piano-back; sides projecting forwardly from the piano-back; arms and foot-members and vertical legs connecting same; the foot members having their rear portion located at and secured to the ends of the piano-back; the previously referred to sides of the piano-case resting on top of said foot-members and being secured thereto; a bottom board extending forwardly of the piano-back underneath said foot-members and being secured thereto.

6. In an upright piano construction, the combination of a piano-back; sides projecting forwardly from the piano-back; arms and foot-members and vertical legs connecting same; the foot members having their rear portion located at and secured to the ends of the piano-back; the previously referred to sides of the piano-case resting on top of said foot-members and being secured thereto; a bottom board extending forwardly of the piano-back underneath said foot-members and being secured thereto; and a lower front panel, the foot-members being vertically notched at their inner faces over the bottom board to receive the lower edge of said panel.

HENRY R. HELLER.
